Patented Jan. 28, 1902.

H. B. WYMAN.

OIL FILTER.

(Application filed Jan. 28, 1901.)

(No Model.)

Fig. 1.

UNITED STATES PATENT OFFICE.

HORACE B. WYMAN, OF LEOMINSTER, MASSACHUSETTS, ASSIGNOR TO THE OIL SAVING MANUFACTURING COMPANY, OF PORTLAND, MAINE, A CORPORATION OF MAINE.

OIL-FILTER.

SPECIFICATION forming part of Letters Patent No. 691,835, dated January 28, 1902.

Application filed January 28, 1901. Serial No. 45,126. (No model.)

To all whom it may concern:

Be it known that I, HORACE B. WYMAN, a citizen of the United States, residing at Leominster, in the county of Worcester and 5 State of Massachusetts, have invented certain new and useful Improvements in Oil-Filters, of which the following is a specification.

My invention relates to improvements in oil-filters, more especially for cleansing and 10 purifying waste oil which has been used in lubricating machinery or for other purposes, and has for its object to provide a device which is simple and inexpensive in construction, effective in use, and which will remove 15 all dirt or other foreign matter from the oil and clean and deliver the oil in a purified state.

The invention consists in the features and combination of features, as hereinafter more 20 fully described and claimed.

Referring to the drawings, Figure 1 is a central vertical section of my invention. Fig. 2 is a top plan view of same.

In the drawings, in which like letters and numerals of reference denote like parts throughout both views, A represents the casing of the oil-filter, divided into a series of compartments B, C, and D, the compartment B having a cover B' and at its upper end a waste-oil receiver E, provided with an inclined bottom F and a pipe G, depending from the same, having a turned-up end H. A perforated plate or strainer I is supported in the waste-oil receiver just above the inclined bottom F of 35 the same.

J is a partition which extends across the compartment B and upward to the point K just below the bottom of the waste-oil receptacle and forms an oil-passage L between 40 said partition J and the division-wall M between the compartments B and C. The division-wall M terminates at its lower end at the point N for the purpose of forming an opening O below the same and is turned inward and formed into a ledge P. The compartment C is provided with a partition Q, extending across the same and upward to the point Q' and provided with ledges R and R', one near the center and the other near the 45 lower end of the said partition Q.

S is a filter adapted to be supported on the

ledges P and R and comprising a bag T, filled, preferably, with pulverized glass or other fine grit T'; but sand or other suitable material may be used. U and V are perforated plates or wire screens between which 55 said bag is held.

W is a compartment in the compartment C, provided with a vertical partition X, terminating at the point X', and a downwardly-inclined bottom Y. A wall Z extends downwardly from the top of the compartment C to the point 1 and then turned laterally to form a ledge 2.

3 is a channel formed between the partition 60 X of the compartment W and the wall Z of compartment C.

4 is a filter adapted to be supported on the ledges 2 and R' and composed of a series of layers or sheets of felt or fibrous material 5 70 and perforated plates or wire screens 6.

The inner wall R³ of the compartment D extends downward to the point 7 and is then turned laterally and formed into a ledge 8.

9 is a ledge which projects laterally from 75 the outer wall 10 of the compartment D.

11 is a filter adapted to be supported on the ledges 8 and 9 of compartment D and composed of one or more layers or sheets of felt or fibrous material 12 and perforated plates 80 or wire screens 13.

R² is a channel between partition Q and wall R³.

A faucet 14 for drawing off the purified oil is provided at the lower end of the compartment D.

Each compartment is provided with a pipe 15, which may have a suitable valve for drawing off all sediment that may collect in said compartment.

16 is a cover for the compartments C and D. The compartment B is filled with water, brine, or other liquid 17 up to about the point 18.

It will be noticed that the upper edge of 95 the vertical partition X of compartment W is lower than the upper edge of the partition J of the compartment B and the upper edge of the partition Q of compartment C is lower than the upper edge of the partition X of 100 compartment W.

The oil after being filtered and used over

many times will separate into two parts—thick flakes of residuum and pure oil. These flakes will not settle and will work through the filter-beds and collect on inclined partitions and 5 accumulate any dirt or grit that may pass through the beds. They will then come off in large flakes and pass on through the filter, carrying the collection of dirt with them, breaking up to accumulate again after passing through the next filter-bed. To avoid 10 this accumulation, I make all partitions vertical, thereby keeping these fine flakes always in solution or mixed with the oil as much as possible until they become solid, 15 when they are taken out of the oil by the filter-beds.

I do not wish to be limited to the precise construction as herein shown and described, as the same may be varied somewhat without 20 departing from the spirit of my invention.

The operation is as follows: The oil is introduced into the waste-oil receiver through a pipe or in any other desired manner and 25 passes through the perforated plate or strainer, down the inclined bottom F, through pipe G, out at the end H of said pipe, up through the water 17, and then the oil will accumulate on top of the water until it flows over the upper 30 edge of the partition J. Then it will go down the channel L, under the lower edge of the wall M, up through the filter S, thence over the upper edge of partition X, down the channel 3, under the lower edge of wall Z, up 35 through the filter 4, over the upper edge of partition Q, down the channel R², under the lower edge of wall R³, up through the filter 11, into the compartment D. Thus it will be seen that the waste oil passes first through a 40 body of water, then through a filter composed of pulverized glass or grit, and finally through filters composed of a series of layers of felt or fibrous material, and by the time it has gone through the last filter it will be thoroughly purified and cleansed and be ready 45 for use.

Having thus described my invention, what I claim is—

1. An oil-filter comprising a compartment 50 having a water filter, a compartment having a filter of pulverized glass and a filter of felt,

a compartment having a filter of felt, and means of communication between said compartments, substantially as shown and described. 55

2. An oil-filter comprising a compartment having an oil-receiver with an inclined bottom, a pipe extending downward from said bottom having its lower end turned upward, a compartment provided with a filter and having a compartment therein with a filter, a compartment provided with a filter, and channels for communication between said compartments, substantially as shown and described. 60

3. An oil-filter comprising a series of compartments, each provided with a filtering medium, one of said compartments provided with a compartment therein having an inclined bottom and a filter, and channels for 70 communication between said compartments, substantially as shown and described.

4. An oil-filter provided with a compartment having water therein, and provided with an oil-receiver having a pipe for feeding said 75 oil to the bottom of said compartment, a compartment provided with a filter, and having a smaller compartment therein provided with a filter, a compartment provided with means 80 for drawing off the purified oil, and channels 85 whereby communication is had between said compartments, substantially as shown and described.

5. An oil-filter provided with a compartment having brine therein and an oil-receiver 85 having a pipe for feeding the oil to the bottom of said compartment, a compartment provided with a filtering medium of fine grit, and having a smaller compartment therein provided with a filtering medium and a compartment 90 provided with a filtering medium and means for drawing off the purified oil, and channels whereby communication is had between said compartments, substantially as shown and described. 95

In testimony whereof I hereto affix my signature in the presence of two witnesses.

HORACE B. WYMAN.
